UNITED STATES PATENT OFFICE.

JOHN T. KIEHNER, OF PHILADELPHIA, PENNSYLVANIA.

BORING-TOOL.

SPECIFICATION forming part of Letters Patent No. 469,503, dated February 23, 1892.

Application filed November 7, 1891. Serial No. 411,173. (No model.)

To all whom it may concern:

Be it known that I, JOHN T. KIEHNER, a citizen of the United States, residing at Philadelphia, in the county of Philadelphia and State 5 of Pennsylvania, have invented certain new and useful Improvements in Boring-Tools, of which the following is a specification.

My invention has relation to tools for boring cylinders and the like, and has for its object to improve the construction and increase 10 the efficiency thereof.

My invention consists in the provision of novel and efficient means whereby the cutting or boring operation may be accomplished 15 in both directions of feed of the boring-bar, the feeding of the latter to be done by hand or automatically, as required, and the tool itself entirely and instantaneously disconnected from or placed in operative relation with the 20 feed-screw, obviating the necessity for running said tool to one of the ends of the screw to secure its disengagement therefrom and the returning of the tool to its initial position thereon before another cut can be made.

My invention further consists in the details of construction and the combinations of parts, as hereinafter fully described and claimed, and as shown in the accompanying drawings, wherein—

Figure 1 is a front elevation, Fig. 2, a rear view with a portion removed and exposing part of the interior mechanism, and Fig. 3 a vertical section, of the improved tool. Figs. 4 and 5 are respectively a plan and 35 edge view of a detail. Fig. 6 is a plan view of the under side of the feed-casing. Fig. 7 is a face view of another detail.

In said drawings, A represents the revolvable feed-casing provided with a bulge a and 40 having therein the eccentric or cam slots a' a² a³, said casing being secured in position by the engagement of the segmental flanges a' a² a³ on the rim a⁷ with the flanges b b' b² of the wheel B and said bulge having a central opening therein for the passage of the feed-screw. The wheel B is secured in position by the washer c, said washer resting in the annular recess b³ in the hub b⁴ of said wheel and being secured by screws, as shown 45 at c², to the inner end of the hub c', said hub having a key or spline c³ for engagement with

a suitable key-seat in and preventing the rotation of said plate on said feed-screw.

The spokes of the wheel B are provided with grooved flanges e e' e², the same forming radial slideways for the nut sections E E' E², which sections are internally threaded and have their bases e³ e⁴ e⁵ formed with lateral ribs e⁶ e⁷ for engagement with the grooves in said flanges.

f f' f² are set-screws passing through and having their heads normally in the slots a' a² a³ and secured in the threaded openings e⁸ e⁹ e¹⁰ in the bases of the nut-sections. Obviously as the feed-casing is rotated (for instance, in the direction indicated by the arrows in Fig. 1) the screws f f' f² will be forced uniformly away from the center, carrying with them and causing the total disengagement of said sections from the correspondingly-threaded feed-screw F, the bulge a affording clearance for the movement of the sections. At the same time the ends of the cam-slots are so disposed relatively to the flanges a⁴ a⁵ a⁶ as to prevent the disconnection of said flanges thereof from the flanges b b' b², with which they interlock, and the consequent displacement of the feed-casing. Thus it is possible by the simple rotation of the casing last mentioned to entirely disconnect the tool from the feed-screw regardless of the position of the same thereon, effecting a great saving in the amount of time and labor necessary for the attainment of the same end.

C' is a recess resulting from the formation of the flange c⁴ on the plate C and provided with a cap or cover M. In said recess are located the gear-wheels G G', the latter being placed side by side and having central openings g' therein, the inner end g² of the boring-bar G² being inserted in the space g³ between the inner edges of the wheels and the hub c' and having thereon the key or spline g, such key or spline engaging with a key-seat in said inner edges. As will be observed, the cover M is provided with a hollow boss m, the same having therein a peripheral groove m', and is secured to the flange c⁴ and the boss c⁵ by the screws m³, thus serving to keep the gears in place in the recess.

c⁶ is a boss on the plate C, having a diminished portion c⁶ eccentrically disposed rela-

tively to the main portion of said boss and supporting the gear H, the latter meshing with the gear G'.

H' is another gear-wheel, the same being sustained on the sleeve or hollow shaft h and having a recess h² in its inner face. Said sleeve has its bearings in the upper part c⁷ of the base-plate, and in the boss h' is provided with the crank H² on one end, has the other end h threaded for reception of the nut k, and has integral therewith the pinion h³.

K is a rod or plunger swivelly secured in the sleeve h by the nut k', said rod at its inner end bearing against the spring h² and having secured therein the pin h³.

L represents a gear-wheel similar to and secured at a distance from the gear H' on the sleeve h, leaving an intermediate space slightly wider than the pin h³, said gear L having in its inner face opposite the recess h² the recess l.

N represents a split collar or clamp having its sections n n' secured together and caused to tightly grasp the boring-bar G² through the passage of the bolts m² through the lugs n² n³ thereof. Said clamp or collar is also provided with a flange n⁴ at its inner end, the same having therein an annular groove n⁵, in which latter is loosely fitted the flange m⁴ of the boss m, while the portion n⁶ of the flange n⁴ loosely engages with the annular groove m⁴ in the hub m. Thus the boring-bar is swivelly connected to the boss m and secured against detachment therefrom upon the operation of the feeding devices in the return direction.

As the nut k is unscrewed the rod K will be drawn outwardly and the pin h³ drawn into the recess h², the result being that the motion which is imparted to the boring-bar by a separate motor, as ordinarily or otherwise, is communicated to the nut-sections through the gears G' H H' and the pinion h³ and wheel B through the medium of the teeth b⁵ on the latter, resulting when said sections are in the position shown in the drawings in the feeding of the boring-tool forwardly or to the right of said drawings. On the other hand, when it is desired to feed said bar backwardly or to the left of the drawings, causing the operation of the cutters on the return movement, the nut k is screwed inwardly, effecting the movement of the rod K and pin h³ in the same direction, causing the engagement of the latter with the recess l in the gear L, which gear meshes with the gear L', said gear L' clearing the gear G and meshing with the intermediate gear L², which latter in turn meshes with said gear G, which is on the boring-bar. Thus the motion of the latter is communicated in a reversed condition to the nut-sections through the gears G L² L' L, pinion h³, and the wheel B, thus attaining the result desired.

When it is desired to feed the boring-bar by hand, the pin h³ is drawn or thrust by the operation of the nut k into the space l' between the gears L and H', as shown in Fig. 3,

permitting said pin to clear the recesses in said gears, whereupon the crank H² is free to be turned and the nut-sections rotated through 70 the pinion h³ and the wheel B.

What I claim as my invention is as follows:

1. In a boring-tool, the combination of the boring-bar, the feed-screw, a sectional rotary nut for engagement with said screw, mechanism for actuating said nut, an oscillating disk provided with eccentric or cam slots, and suitable projections, sustained by the nut-sections, engaging with said slots, substantially as and for the purpose specified. 80

2. In a boring-tool, the combination of the boring-bar, the feed-screw, a sectional rotary nut for engagement with said screw, a toothed wheel affording radial slideways for and carrying said sections, and mechanism for actuating said wheel, substantially as and for the purpose specified. 85

3. In a boring-tool, the combination of the boring-bar, the feed-screw, a sectional nut for engagement with said screw, an oscillating disk provided with eccentric or cam slots for reception of projections on the nut-sections, a toothed wheel affording radial slideways for and carrying said sections, and mechanism for actuating said wheel, substantially as and for the purpose specified. 90

4. In a boring-tool, the combination of the boring-bar, the feed-screw, a sectional nut for engagement with said screw, an oscillating disk provided with eccentric or cam slots for reception of projections on the nut-sections, a toothed wheel affording radial slideways for said sections, actuating mechanism for said wheel, and means for reversing the direction of movement of said mechanism, substantially as and for the purpose specified. 105

5. In a boring-tool, the combination of the boring-bar, the feed-screw, a sectional nut for engagement with said screw, an oscillating disk provided with eccentric or cam slots for reception of projections on the nut-sections, a toothed wheel affording radial slideways for said sections, a train of gears intermediate said wheel and the boring-bar, having therein a pair of oppositely-disposed gears provided with a recess in their opposite faces and located at a distance apart, a hollow journal-support for the recessed gears, having a pinion meshing with said toothed wheel, a spring-controlled laterally-movable rod in said journal, and a pin in said rod for alternate engagement with the respective recesses, substantially as and for the purpose specified. 110

6. In a boring-tool, the combination of the boring-bar, the feed-screw, actuating mechanism intermediate the bar and screw, the tool-casing provided with an annular flange, and a split collar provided with means whereby it is clamped on said bar and having therein an internal annular groove for reception of 125 said flange, substantially as and for the purpose specified.

7. In a boring-tool, the combination of the boring-bar, the feed-screw, a sectional nut for

engagement with said screw, the casing A, having the slots a a a therein for reception of projections on the nut-sections, the wheel B, affording slideways for said sections, said 5 wheel and casing having the interlocking flanges b b' b^2 and a^4 a^5 a^6 , and suitable gears intermediate the wheel B and the boring-bar, substantially as and for the purpose specified.

8. In a boring-tool, the combination of the 10 boring-bar, the feed-screw, a train of gears intermediate said bar and screw, the gears L and H' in said train and having therein the recesses l and h^2 , respectively, the sleeve h , supporting said gears and threaded for reception 15 of the nut k , the rod K in said sleeve and secured by the nut k' , the spring k^2 , and the pin h^3 in said rod for engagement alternately with said recesses, substantially as and for the purpose specified.

20 9. In a boring-tool, the combination of the boring-bar, the feed-screw, the base-plate C, provided with the flange c^4 , suitable gears intermediate said screw and bar in the recess

formed by said flange, the cover M, provided with the boss m , and the clamp N, secured to the 25 boring-bar and having the internal groove n^5 for reception of the flange m^4 of said boss, substantially as and for the purpose specified.

10. In a boring-tool, the combination of the boring-bar provided with the key g , the gear G', having a seat for the key, the gear H, journaled on the portion c^6 of the boss c^5 , the gear H', and the gear I, suitably supported and provided with the recesses h^2 and l , the gear L' on said boss, the gear L², the gear G', 30 having a seat for the key g , and means for conveying the motion of the gears to the feeding devices, substantially as and for the purpose specified.

In testimony whereof I have hereunto set 40 my hand this 27th day of October, A. D. 1891.

JOHN T. KIEHNER.
